Inventor:

UNITED STATES PATENT OFFICE.

SAMUEL I. RUSSELL, OF CHICAGO, ILLINOIS.

DESIGN FOR BASKETS.

Specification forming part of Design No. 6,508, dated March 18, 1873.

To all whom it may concern:

Be it known that I, SAMUEL I. RUSSELL, of Chicago, Cook county, Illinois, have invented a Design for Baskets, of which the following is a specification:

The nature of my design is fully represented in the accompanying photographic illustration, to which reference is made, there being four figures—

Figure 1 showing a basket with its cover on. Fig. 2 shows the same form of basket with the cover raised; Fig. 3, the same with cover removed; Fig. 4, the same with a short standard between the base and basket proper.

A represents the base, B the body, and C the cover.

The bottom portion of the body of the basket swells out in a graceful curve from the

base A, to which the body is secured, and the main portion of the body is carried up in the form shown. Around the top of the body is an ornamental band or molding.

In Fig. 4 the base is precisely the same as in the other figures; and the body is the same, except that it is not carried up as high as in the other figures; and the ornamental band or rim around the top is the same.

What I claim as my invention is—

A design for a basket having a base, A, a body, B, and ornamental band *a*, all substantially as described and shown, either with or without the cover C.

S. I. RUSSELL.
